(57) CLAIM

The ornamental design for a two-sided electric frying pan, as shown and described.

DESCRIPTION

FIG. 1 is a perspective view of a two-sided electric frying pan;

FIG. 2 is a left elevation view of the invention illustrated in FIG. 1;

FIG. 3 is a right elevation view of the invention illustrated in FIG. 1;

FIG. 4 is a front elevation view of the invention illustrated in FIG. 1;

FIG. 5 is a rear elevation view of the invention illustrated in FIG. 1;

FIG. 6 is a top plan view of the invention illustrated in FIG. 1; and,

FIG. 7 is a bottom plan view of the invention illustrated in FIG. 1.
